CLAIM

The ornamental design for a display panel or screen with an animated graphical user interface, as shown and described.

DESCRIPTION

FIG. 1 is a front view of a first embodiment of a display panel or screen with a first image of an animated graphical user interface showing my new design; and FIG. 2 is a second image thereof.

FIG. 3 is a front view of a second embodiment of a display panel or screen with a first image of an animated graphical user interface showing my new design; and, FIG. 4 is a second image thereof.

The even dash broken lines showing of the display panel or screen and portions of the graphical user interface are for the purpose of illustrating environmental structure and form no part of the claimed design.

The appearance of the transitional image sequentially transitions between the images shown in FIGS. 1-2 and FIGS. 3-4.

The process or period in which an image transitions to another forms no part of the claimed design.
